UNITED STATES PATENT OFFICE.

JACOB G. GERHART, OF FREDERICKSBURG, PENNSYLVANIA.

AIR-PUMP.

1,351,847.

Specification of Letters Patent. Patented Sept. 7, 1920.

Application filed November 14, 1919. Serial No. 337,924.

To all whom it may concern:

Be it known that I, JACOB G. GERHART, a citizen of the United States, residing at Fredericksburg, in the county of Lebanon and State of Pennsylvania, have invented 5 certain new and useful Improvements in Air-Pumps, of which the following is a specification.

This invention relates to certain improvements in air pumps, and has relation more particularly to a device of this general character especially designed and adapted for use in the inflating of pneumatic bodies, such as automobile tires or the like, and it 15 is an object of the invention to provide a novel and improved device of this general character embodying two relatively movable members coacting in a manner whereby the pump is double acting.

Another object of the invention is to provide a novel and improved device of this general character comprising two tubular members telescoping one within the other, and wherein one of said members is mounted 25 for rectilinear movement with respect to the other, and wherein said members coact in a manner to discharge a substantially constant flow of air under pressure during a working operation of the pump.

Another object of the invention is to provide a novel and improved pump of this general character embodying two telescopically coacting members movable one with respect to the other, and wherein air, under 35 pressure, is discharged from one of the members upon relative movement of the members in either direction.

An additional object of the invention is to provide a novel and improved pump of 40 this general character embodying a tubular member or cylinder coacting with a piston arranged therein, and wherein the piston is provided with means movable therewith for lubrication.

The invention consists in the details of 45 construction and in the combination and arrangement of the several parts of my improved air pump, whereby certain important advantages are attained and the device 50 rendered simpler, less expensive and otherwise more convenient and advantageous for use, as will be hereinafter more fully set forth.

The novel features of my invention will 55 hereinafter be definitely claimed.

In order that my invention may be the

better understood, I will now proceed to describe the same with reference to the accompanying drawings, wherein:

Figure 1 is a view partly in elevation and 60 partly in longitudinal section of a pump constructed in accordance with an embodiment of my invention;

Fig. 2 is an enlarged fragmentary view 65 partly in longitudinal section and partly in elevation illustrating the lubricating means carried by the piston working within the inner tubular member or cylinder, and,

Fig. 3 is a view in elevation of one of the parts comprised in the lubricating means, 70 particularly illustrated in Fig. 2.

As disclosed in the accompanying drawings, B denotes an elongated tubular member or cylinder of brass or other material, and which has one end portion closed by a 75 plug 1, said plug being herein shown as being partly threaded within an end portion of the barrel or cylinder B. The outer end portion of the plug 1 is provided with an extension 2, herein disclosed as threaded 80 within a pocket 3, formed in a base member M. The inner end of the extension 2 is defined by an outstanding shoulder 4 for limiting the extent of insertion of the extension 2 within the pocket 3, so that the maintenance 85 of a chamber a at the inner end of the pocket 3 is assured. The plug 3 has disposed therethrough substantially axially, a restricted port 5. In communication with the chamber a is the bore 6 of an outstanding 90 nipple 7. Secured to the nipple 7 in any desired manner is an end portion of a flexible tubing 8, adapted to be suitably engaged with an inflating valve of a pneumatic tire, or to be directed to any suitable place of 95 delivery.

C denotes a second tubular member or cylinder of desired length, and preferably of brass. The member or cylinder C has its internal diameter greater than the major 100 diameter of the member or cylinder B. Suitably fixed within one end portion of the member or cylinder C is a collar 9; provided with an internal shoulder 10. The internal surface of the collar 9 in advance or outwardly of the shoulder 10 is screw threaded to permit engagement therewith of an end portion of a guide sleeve 11. The sleeve 11 extends a material distance outwardly from the member or cylinder C.

Extending within the member or cylinder C and through the sleeve 11 is the member

or cylinder B, hereinbefore referred to, said sleeve closely fitting the member or cylinder B, and operating to hold the member or cylinders B and C against relative lateral movement when the same are in extended relation one with respect to the other.

Also surrounding the member or cylinder B, and having close contact therewith is an annular or cylindrical packing 12 of fiber, leather or other suitable material. One end portion of the packing 12 is provided with the outstanding continuous flange 14, which is engaged between the shoulder 10 and the adjacent end of the sleeve 11, whereby said packing 12 is effectively maintained in applied position. The packing 12 is of a length to extend inwardly of the member or cylinder C, a decided distance beyond the upper face of the collar 9. The packing 12 operates to prevent leakage between the member or cylinder B and the collar 9, and particularly when the member or cylinder C is on its compression stroke as the pressure of the air within the member or cylinder C, and surrounding the member or cylinder B, will force the extended end portion of the packing 12 in close engagement with the member or cylinder B.

The opposite end portion of the member or cylinder C has threaded or otherwise secured thereto a perforated cap 15. Secured, as at 16, to the axial center of the cap 15 is a rod 17. The rod 17 extends inwardly of the member or cylinder C, and within the member or cylinder B, and the inner end portion of said rod 17 has secured thereto a piston P, to be hereinafter more particularly referred to.

Threaded to, or otherwise secured around the end portion of the member or cylinder B, remote from the plug 1, is a sleeve 18, extending outwardly and beyond the adjacent end of the member or cylinder C. The inner end of the sleeve 18 is defined by an outstanding continuous flange 19, and engaging the outer face of said flange 19 is an inwardly facing cup washer 20 of leather or other suitable material. The cup washer 20 is clamped to the flange 19 by the nut 21 threaded upon the sleeve 18, as is clearly illustrated in Fig. 1 of the accompanying drawings.

Extending within the adjacent end portion of the member or cylinder 9 is an annular member 22, having its outer end defined by an outstanding annular flange 23 engaging the adjacent end of the member or cylinder B. The rod 17 extends through the member 22. Surrounding the rod 17 and extending within the bore of the member 22 is a packing member 24 having its outer portion defined by an outstanding continuous flange 25 overlying the adjacent end of the member 22 and the flange 23 thereof. The packing member 24 is clamped to the

member 22 and maintained in applied position by the plug 26, threaded in the outer end portion of the sleeve 18. The packing member 24 operates to prevent leakage at the adjacent end of the member or cylinder B. 70

The piston P hereinbefore referred to, comprises a disk or plate 27 securely engaged with the rod 17 at a distance inwardly of the inner or inserted end thereof, and clamped to the under face of the disk or 75 plate 27 is a cup washer 28, of leather or the like.

The cup washer 28 may be held in applied position in any desired manner, but it is preferred that the structure be employed 80 which is particularly illustrated in Fig. 2 of the drawings. A plate 29 surrounds the rod 17 and bears against the outer face of the cup washer 28. A second plate 30 surrounds the rod 17 and is provided with an 85 inwardly directed hub 31 for maintaining the plates 29 and 30 in spaced relation. The marginal portion of the plate 30 is defined by an inwardly directed flange 32 bridging the space between the plates 29 and 30, and 90 provided with the spaced recesses or slots 33. Threaded upon the rod 17 is another plate 34, which operates to maintain the plates 29 and 30 in assembled relation, and to clamp the cup washer 28 in working position. The plate 34 is of a diameter in excess of the plate 30 with which it coacts, and is of a major diameter slightly less than the internal diameter of the member or cylinder B. It is also preferred that the edge of the 100 plate 34 be slightly tapered in a direction toward the cup washer 28. It is also to be noted that the plate 34 is of a diameter to underlie the free marginal edge of the cup washer 28, and in close proximity thereto. 105

The member or cylinder B, at a point immediately adjacent the annular member 22 is provided with the ports 25 affording communication between the interior thereof, and the interior of the member of cylinder C. 110

The end portion of the member or cylinder C, at a point preferably closely adjacent the cap 15 is provided with the oppositely directed hand grasps 35, whereby the cylinder or member C may be manually operated to reciprocate the same with respect to the member or cylinder B.

Carried by the outer face of the plug 26 is a buffer 37 herein disclosed as a coil 120 spring encircling the rod 17. The buffer 37 coacts with the cap 15 upon undue movement of the member or cylinder C in one direction. The base member M may be of any desired configuration or dimension, but, 125 as this forms no part of my present invention, it is not believed that a detailed description and illustration is necessary.

Upon movement of the member or cylinder C in a direction away from the base 130

member M, the air within said member and surrounding the member or cylinder C is forced into the member or cylinder B through the ports 35, and passes by the cup washer 28 and into the chamber *a*, and out through the nipple 7, and upon reversing movement of the member or cylinder C the air within the member or cylinder B is forced outwardly therefrom by the piston 10 P and, due to the fact that the cup washer 28, has the requisite contact with the inner face of said member or cylinder B. Upon this second movement of the cylinder or member C a fresh supply of air is being admitted therein inwardly of the cup washer 28, said air entering through the openings or perforations 15' in the cap 15, and readily passing the cup washer 19 owing to the flexibility thereof.

20 During a working operation it is found of utmost importance that provision be made for lubricating the member of cylinder C and the piston P coacting therewith, as the heat generated thereby is such as to 25 otherwise affect the efficiency of the device. The requisite lubrication is obtained by arranging between the plates 29 and 30 and inwardly of the flange 32, a case 38 of lubricant, which liquefies under heat. The lubricant as it liquefies passes through the slots or recesses 33, and engages the cup washer 28. This molten lubricant is prevented from dropping directly through the member or cylinder B by the plate 34, and which 35 plate also serves to deflect the molten lubricant to the inner wall of the member or cylinder B. The tapering edge of the plate 34 is of decided advantage because, after the pump becomes inactive, the molten lubricant congeals, and said tapering edge serves to retain a portion of said congealed lubricant, so that upon further use of the pump, the lubricant is in position to immediately 40 become active.

45 The outer face of the plate 30 is convex, and the plate 34 at diametrically opposed points is provided with openings therethrough. By this arrangement the air passes through the openings in the plate 34 and strikes the convex face of the plate 32 and spreads out against the cup washer 28. The operation just referred to occurs upon the downward or compressing stroke of the piston P, and whereby the efficiency 55 of the pump is materially facilitated. This spreading of the air also facilitates the proper distribution of the lubricant.

From the foregoing description it is thought to be obvious that an air pump 60 constructed in accordance with my invention is particularly well adapted for use by reason of the convenience and facility with which it may be assembled and operated, and it will also be obvious that my 65 invention is susceptible of some change and

modification without departing from the principles and spirit thereof, and for this reason I do not wish to be understood as limiting myself to the precise arrangement and formation of the several parts herein shown in carrying out my invention in practice except as hereinafter claimed.

I claim:

1. A pump of the class described comprising two tubular members, one telescoping 75 within the other, the inner member being provided with a discharge opening at one end portion, said members having rectilinear movement one with respect to the other, an annular member arranged within 80 the inserted end portion of the inner tubular member and provided with an outstanding flange engaging the adjacent end of said inner member, a perforated head closing the outer end portion of the outer 85 member, an inwardly directed rod secured to said head and extending through the bore of the annular member and within the inner tubular member, a piston working 90 within the inner tubular member and operatively engaged with the rod, a packing surrounding the rod and extending within the bore of the annular member, said packing having its outer end portion defined by an outstanding flange overlying the outer face 95 of the annular member, a sleeve engaged with and surrounding the inserted end portion of the inner tubular member, said sleeve being internally and externally threaded, the inner end portion of said 100 sleeve being defined by an outstanding flange, a plug engaged within the outer end portion of the sleeve and surrounding the rod, said sleeve coacting with the packing and the flange thereof for clamping 105 said packing in applied position, a cup washer surrounding the lower portion of the sleeve and coacting with the inner wall of the outer tubular member, and a nut 110 threaded upon the outer end portion of the sleeve and coacting with the cup washer to clamp the same to the flange of the sleeve, the wall of the inner tubular member being provided with a port affording communication with the outer tubular member. 115

2. A pump of the class described comprising two tubular members, one telescoping within the other, the inner member being provided with a discharge opening at one end portion, said members having rectilinear movement one with respect to the other, an annular member arranged within 120 the inserted end portion of the inner tubular member, and provided with an outstanding flange engaging the adjacent end of said inner member, a perforated head closing, the outer end portion of the outer member, an inwardly directed rod secured to said head and extending through the bore 125 of the annular member and within the inner 130

- tubular member, a piston working within the inner tubular member and operatively engaged with the rod, a packing surrounding the rod and extending within the bore 5 of the annular member, said packing having its outer end portion defined by an outstanding flange overlying the outer face of the annular member, a sleeve engaged with and surrounding the inserted end portion of the 10 inner tubular member, said sleeve being internally and externally threaded, the inner end portion of said sleeve being defined by an outstanding flange, a plug engaged with-in the outer end portion of the sleeve and 15 surrounding the rod, said sleeve coacting with the packing and the flange thereof for clamping said packing in applied position, a cup washer surrounding the lower portion of the sleeve and coacting with the in- 20 ner wall of the outer tubular member, and a nut threaded upon the outer end portion of the sleeve and coacting with the cup washer to clamp the same to the flange of the sleeve, the wall of the inner tubular member being 25 provided with a port affording communication with the outer tubular member, said port being positioned at a point in close proximity to the sleeve and inwardly there- 30 of and within the cup washer.
3. A pump of the class described comprising two tubular members, one telescoping within the other, the inner member being provided with a discharge opening at one end portion, the inner member being also 35 provided with a port affording communication between the interior of said member and the interior of the outer tubular member, the outer end of the outer tubular member being provided with a head having an inlet opening, a rod secured to said head and extending within the inner tubular member, a piston working within said inner tubular member and operatively engaged with the rod, a piston carried by the in- 40 inserted end portion of the inner tubular mem- 45 ber and coacting with the outer tubular mem-
- ber, a sleeve mounted upon the inner tubular member, a packing sleeve surrounding the inner tubular member and having one end portion contacting with the inner end 50 of the sleeve, said end portion of the pack- ing being defined by an outstanding flange, a collar engaged within the inner end por- tion of the outer tubular member and in- 55 internally threaded, the inner end portion of the sleeve engaging the internally threaded portion of the collar, said packing sleeve be- 60 ing of a length to extend inwardly of the collar.
4. A pump of the class described com- 65 prising two tubular members, one telescoping within the other, the inner member be- 70 ing provided with a discharge opening in one end portion, the inner member being also provided with a port affording com- 75 munication between the interior of said member above a piston therein and the in- 80 terior of the outer tubular member, the outer end of the outer tubular member being provided with a head having an inlet open- 85 ing, a rod secured to said head and extend- 90 ing within the inner tubular member, a pis- ton working within said inner tubular mem- ber and operatively engaged with the rod, a piston carried by the inserted end por- tion of the inner tubular member and co- acting with the outer tubular member, a sleeve mounted upon the inner tubular mem- 95 ber, a packing sleeve surrounding the inner tubular member and having one end por- tion contacting with the inner end of the sleeve, said end portion of the packing be- 100 ing defined by an outstanding flange, a collar engaged with the inner end portion of the outer tubular member and internally threaded, the inner end portion of the sleeve engaging the internally threaded portion of the collar, said packing sleeve being of a length to extend inwardly of the collar.

In testimony whereof I affix my signature.

JACOB G. GERHART.
